UNITED STATES PATENT OFFICE

HARRY L. GUY, OF CHICAGO, ILLINOIS, ASSIGNOR OF ONE-HALF TO HOMER J. LUCE, OF CHICAGO, ILLINOIS

DESIGN FOR A ROOFING UNIT

Application filed May 8, 1931. Serial No. 39,778. Term of patent 14 years.

To all whom it may concern:

Be it known that I, HARRY L. GUY, a citizen of the United States, residing at Chicago, in the county of Cook and State of Illinois, have invented a new, original, and ornamental Design for Roofing Unit, of which the following is a specification, reference being had to the accompanying drawing, forming part thereof.

In the drawing:

The figure is a plan view of an individual roofing strip or unit embodying the ornamental design.

I claim:

The ornamental design for a roofing unit as shown.

HARRY L. GUY.
